UNITED STATES PATENT OFFICE

164,277

DANGER SIGNAL

Virgil S. Berry, Moss Point, Miss.

Application June 30, 1950, Serial No. 10,906

Term of patent 3½ years

(Cl. D72—1)

To all whom it may concern:

Be it known that I, Virgil S. Berry, a citizen of the United States of America, residing at Moss Point, in the county of Jackson and State of Mississippi, have invented a new, original, and ornamental Design for a Danger Signal, of which the following is a specification, reference being had to the accompanying drawing, forming part thereof, in which:

Figure 1 is a perspective view of a danger signal showing my new design.

Fig. 2 is a side elevational view of the signal.

Fig. 3 is an end elevational view of the danger signal.

The side opposite to that shown in Fig. 1 is the same as that shown in Fig. 1 and the end opposite the end shown in Fig. 3 is the same

as that shown in Fig. 3 except that the switch is omitted.

I claim:

The ornamental design for a danger signal, as shown and described.

VIRGIL S. BERRY.
